UNITED STATES PATENT OFFICE.

JOHN F. WILLIAMS, OF KANSAS CITY, KANSAS, ASSIGNOR TO THE ECONOMY GAS LAMP COMPANY, OF KANSAS CITY, MISSOURI.

DESIGN FOR A LAMP-FIXTURE.

SPECIFICATION forming part of Design No. 30,148, dated February 7, 1899.

Application filed December 24, 1898. Serial No. 700,290. Term of patent 14 years.

To all whom it may concern:

Be it known that I, JOHN F. WILLIAMS, a citizen of the United States, residing at Kansas City, in the county of Wyandotte and State of Kansas, have invented and produced 5 a new and original Design for a Lamp-Fixture, of which the following is a specification.

My present invention relates to a new and original design for lamp-fixtures, of which the 10 following is a specification, reference being had to the annexed drawing, wherein the frame is shown in elevation.

The fixture consists of the arm A, provided with a hook B at its upper end, a curved arm 15 C, extending out from said arm A, as shown, and carrying a reservoir D. A fitting E is carried by the lower end of arm A, and ex-

tending out by said arm is a member F, connected by a curved section G to a member H, which stands substantially parallel to the 20 member F. An arm I extends down from the fitting E, said arm being curved, as shown, at its lower end and carrying a burner-support J.

Having thus described my invention, what 25 I claim is—

The design for a lamp-fixture as herein shown and described.

In witness whereof I hereunto set my hand in the presence of two witnesses.

JOHN F. WILLIAMS.

Witnesses:

M. M. SWEETMAN,
C. M. BROWN.
